COMPRESSOR

Joseph C. McCune, Edgewood, Pa., assignor to
The Westinghouse Air Brake Company, Wil-
merding, Pa., a corporation of Pennsylvania

Application February 24, 1934, Serial No. 712,731

3 Claims. (Cl. 230—211)

My invention relates to fluid compressors and particularly to electric motor driven compressors of the multi-cylinder type.

It is an object of my invention to provide a compact and relatively light weight multi-cylinder compressor.

Another object is to provide a self-contained motor driven fluid compressor unit wherein a sectional casing constituting the housing for the compressor, the motor, and a fan may be readily formed and assembled into a compact unit occupying a minimum of space.

Another object of my invention is to provide an improved fluid compressor casing adapted to form a crank case chamber, a cooling chamber or passage, a discharge chamber or passage, and an intake chamber or passage within the casing.

Another object is to provide a compressor unit wherein fluid to be compressed may be supplied to the compressor cylinders under pressure from the cooling chamber of the compressor or from an external source.

Another object is to provide a highly efficient fluid compressor capable of operating at high speeds which I, in part, accomplish by radially disposing the compressor cylinders and by providing fluid inlets for the compressor cylinders, which inlets are controlled by the corresponding fluid compressing pistons in the respective cylinders.

Another object is to provide an improved compressor unit having a casing for a radial cylinder type compressor, a fan, and a driving motor, in which the cooling air for the motor and the compressor enters one end of the casing axially, passes the motor, and discharges past the compressor cylinders through radial openings at the other end of the casing, which openings respectively cooperate with the compressor cylinders.

Another object is to provide a compressor unit, having above noted characteristics, with improved means for separating foreign particles from the cooling air before the cooling air contacts motor and compressor parts.

A further object is to provide a compressor wherein an improved plunger pump serves to circulate fluid lubricant in the lubricating system for the moving parts.

An additional object is to provide a compressor wherein is employed an improved discharge valve device which may be assembled as a unit and removed from the compressor as a unit for the purpose of inspection, repair or replacement.

The above objects and other additional objects of my invention that will be made apparent subse-

quently are attained by means of the compressor unit hereinafter described and illustrated in the accompanying drawings, wherein

Fig. 1 is a longitudinal sectional view, partly in elevation, of a compressor unit embodying features of the invention;

Fig. 2 is a transverse sectional view through the unit taken on the line 2—2 of Fig. 1;

Fig. 3 is a fragmental sectional view of a detail, taken on the line 3—3 of Fig. 2;

Fig. 4 is a transverse sectional view of the unit taken on the line 4—4 of Fig. 1, with a portion broken away;

Fig. 5 is a transverse sectional view of the unit taken on the line 5—5 of Fig. 1;

Fig. 6 is a transverse sectional view of the unit taken on the line 6—6 of Fig. 1;

Fig. 7 is a fragmental sectional view through a compressor cylinder, taken on the line 7—7 of Fig. 1;

Fig. 8 is a top plan view of a fragment of the unit showing a compressor cylinder and head;

Fig. 9 is a fragmental vertical sectional view of a cylinder and head showing an improved form of discharge valve device;

Fig. 10 is an enlarged isometric view of the spring retainer of the discharge valve shown in Fig. 9;

Fig. 11 is a fragmental sectional view of the plunger pump of the lubricating system; and

Fig. 12 is a transverse sectional view of the plunger pump, taken on the line 12—12 of Fig. 11.

Referring to the drawings and particularly to Figs. 1 to 6, the compressor unit comprises a casing or housing made of metal section comprising a fan housing section 12 including a part of the motor housing or casing, motor casing sections 13 and 14 and a compressor casing section 15 which contains a suitable number of radially disposed compressor cylinders 16 such as the three shown, crank arms of the compressor and the lubricant circulating system for the compressor.

According to my invention, the compressor casing 15 is divided by partition walls 21 and 22 into a crank chamber 17, a cooling chamber 18 through which cooling air is circulated in a manner to be hereinafter described, and a compressed air discharge chamber 19. The wall 21 has three radially disposed cylinder portions 23, as shown in Figs. 1 and 5 in which the compression cylinders 16 are respectively mounted so that an annular inlet chamber 20 for the air to be compressed is formed between each of the cylinders 16 and the wall portion 23. Furthermore, the cylinders are suitably adapted to be removable.

from the wall portions 23, as shown in Figs. 1 and 5, by being lifted radially outward, for purposes of repair or replacement.

The annular inlet chamber 20 surrounding each compression cylinder 16 communicates with an arcuate inlet chamber 24, as shown in Figs. 1 and 4, through passages 25, the inlet chamber 24 being formed in the casing section 14, the upper portion of the chamber being connected to an inlet pipe 30 which is open to the atmosphere. The wall 26 of the casing section 14 is provided with threaded openings 27 for receiving threaded plugs 28 which may be removed in the event that it is desired to supply air to the inlet chamber 24 through the openings 27 from the motor chamber 11 for a purpose to be hereinafter described.

The upper end of each of the compression cylinders 16 is provided with longitudinally extending vanes 29, as shown in Figs. 1, 7, and 8, 20 which project radially from the cylinder wall within the radial air discharge passages 31 in the casing section 15, so that the air forced through the motor chamber 11 into the cooling air chamber 18 is caused to flow past the cooling vanes 29 25 for the purpose of maintaining the cylinders and associated parts at the proper operating temperature.

The upper end of each of the compression cylinders 16 is closed by means of a head casing 32, 30 as shown in Figs. 1, 5, and 9, which is suitably secured to the casing 15 as by machine screws or bolts, and which serves to secure the cylinders 16 to the wall portions 23. Each of the head casings 32 is provided with a discharge 35 chamber 33 containing a discharge valve device to be hereinafter described, the discharge chamber 33 being connected to the discharge chamber 19 in the casing section 15 by means of passages 34 which register with openings 35 in the discharge chamber 19. The discharge chamber 19 is adapted to be connected to a receiver, not shown, by a discharge pipe 36, Figs. 5 and 6, one side of the discharge chamber being provided with a threaded opening 37 for receiving a discharge pipe in the event that it is desired to connect the discharge pipe to the opposite side of the compressor. As indicated in Fig. 5 the threaded opening 37 is closed by means of a screw plug 38.

The head casing 32 is provided with radial cooling fins 39 spaced apart so that air passages 40, Figs. 7 and 8, are provided between them through which air passing to the atmosphere from the radial passages 31, flows, thereby carrying away 55 the heat conducted to the head from the associated parts of the mechanism.

A feature of the improved compressor apparatus is the discharge valve device which, as will hereinafter appear, is a self-contained unit which 60 may be assembled in the mechanism as a unit and withdrawn therefrom for the purpose of inspection and repair as a unit.

Referring to Figs. 9 and 10 the discharge valve device includes a valve seat disc 41 that is adapted to be seated in an annular recess 42 in the outer face of the compression cylinder 16 and which is provided with a series of discharge ports 43 that are adapted to be closed by an annular valve disc 44. Disc 44 is mounted for sliding engagement upon a central stem 45 which is integral with the valve seat disc 41 and which is provided at its end with an enlarged head 46 for a purpose that will hereinafter appear. A tubular spring retainer 47 is provided, having a flange 75 48 that is adapted to be centered in a circular

recess 49 in the head casing 32 when the head is in assembled position upon the cylinder 16. The spring retainer 47 is provided at its other end with a portion 51 having an inwardly directed flange 52 that is provided with a slot 53 of such shape that it permits of the assembly of the spring retainer upon the valve seat disc 41 by a lateral movement with respect to the disc, the head 46 of the stem 45 serving to limit the longitudinal displacement of the spring retainer 47 with respect to the disc 41 when the head casing 32 is removed from the cylinder casing 16. A helical spring 53 is disposed concentrically around the spring retainer 47 and extends between the flange 48 of the latter and the valve disc 44 to yieldingly 15 retain the valve disc upon the seat disc whereby the discharge ports 43 are closed. The fluid compressed within the compression chamber of the cylinder 16 passes into the discharge chamber 33 in the head casing 32 when the pressure of 20 the fluid compressed therein is sufficient to overcome the combined pressure of the fluid within the discharge chamber 33 and that exerted by the spring 53 which opposes opening movement of the valve disc 44.

From the foregoing, it is apparent that the discharge valve assembly consists of the seat disc 41, the valve disc 44, the spring retainer 47 and the spring 53, which elements are retained in assembled position by reason of the engagement 30 of the enlarged head 46 with the flange 52 of the spring retainer. To assemble the discharge valve unit upon the cylinder casing 15, the valve disc seat 41 is first placed in the recess 42. A gasket 54 is then placed over the valve seat disc 35 41 and the head casing 32 is next placed over the spring retainer 47 so that the flange 48 enters the recess 49, as indicated in Fig. 9. When the head casing 32 is forced into engagement with the end of the wall of cylinder 16 by means of the 40 head bolts 55, the spring 53 is compressed and the parts occupy the position shown in Fig. 9. Opening travel of the valve disc 44 is limited by engagement of the disc with the flange 52 of the spring retainer 47.

When it is desired to inspect or repair the discharge valve, the head casing 32 is first removed after which the discharge valve unit may be readily removed as a unit.

The compressor unit herein disclosed is of the 50 multi-cylinder type comprising, for example, three compression cylinders, each of which contains a piston 56 operated by the usual connecting rod 57 that is connected by means of anti-friction bearings 58 to a crank arm 59 carried on the end of a crank shaft 61. The crank shaft is mounted for rotation in antifriction bearings 62 and 63, secured within the casing sections 14 and 12, respectively, and is provided with a counter-weight 64 for counterbalancing the crank arm 59 and its 60 associated moving parts. As will be clearly seen in Fig. 1, the motor armature 65 is secured to shaft 61 between the bearings 62 and 63, and the rotative impulse is thus applied to the shaft by the motor.

The motor armature and its associated parts, as well as the compressor cylinders 16 are adapted to be cooled by air drawn into the casing sections through an end opening 66 in the casing section 12. A protection screen 67 is provided to cover the opening 66 and a conical inlet collar 68 which is secured to the casing section 12 with the screen, serves to direct air into the central portion of a 70 centrifugal fan 69.

The fan 69 is of the centrifugal blower type, in 75

which a series of spaced arcuate vanes 71 are arranged about the periphery of the disc-like body 72 as indicated in Figs. 1 and 2 so that when the fan is rotated by the motor in a clockwise direction in Fig. 2, the air drawn through the screen 67 and inlet collar 68 leading to the central portion of the fan is discharged radially and in the direction of rotation of the fan so that the air discharged from the fan is given a gyratory motion within the fan chamber 73. The wall of the fan chamber casing section 12 is formed in the shape of a spiral, with an inner extension 74 thereof terminating at a point 75 adjacent the periphery of the fan, so that a discharge channel 76 is defined by the extension 74, which channel expands spirally in cross-sectional area to a point opposite the point 75 at the extremity of the extension 74. From a point opposite the point 75, the channel defined by the outer face of the extension 74 and the outer wall of the casing section 12, diminishes in cross-sectional area until it reaches an opening 77.

A hinged cap or cover 78 is yieldingly held in a position to close the opening 77 by a spring 79 under the control of a latch member 81 which is pivotally connected to the casing 12 and which engages the spring 79 so that when the latch member 81 is in the position shown, the spring is retained in closure closing position.

The partition wall 82 of the casing section 12, which constitutes one of the walls of the channel 76, is provided with an opening 83 in a part thereof between the wall 74 and the outer wall of the casing section 12, through which opening 83 the air discharged from the fan within the fan chamber may flow to the motor chamber 11. A screen 84 that is removably connected to the casing section 12 by means of the screws 85, is provided for covering opening 83. The lower extremity of the passage 76 adjacent the opening 77 constitutes a trap for receiving foreign particles carried into the fan chamber in suspension in the air, the wall 74 being provided with a downwardly depending web 86 for preventing such a back flow of air from the trap as would carry the foreign particles out of the trap. Accumulations of foreign particles within the trap may be removed through the opening 77 by manually opening the cover 78 against the action of the spring 79.

A further feature of the improved compressor mechanism is an improved pump for circulating fluid lubricant so that the lubricant is forced through a passage 87 into the crank arm 59 from which it flows to the bearings 58 for the connecting rods through passages 88. Referring to Figs. 1, 11 and 12, the pump mechanism comprises a member forming a compression chamber 89, removably secured to casing section 15, and a pump piston 91 which is adapted to reciprocate within the chamber 89. The piston 91 is provided with a valve chamber 92 that is open to the crank chamber 17 through an opening 93 through which fluid lubricant in the crank chamber 17 may flow into the valve chamber 92 of the piston 91. The piston is provided at its lower end with a port or opening 94 through which fluid flows from the chamber 92 into the compression chamber 89. A reciprocating plunger 95 for moving piston 91 is provided with an enlarged head 96 which is adapted to reciprocate through a short distance within the chamber 92, as will be hereinafter further explained, the plunger also having a longitudinal passage 97 extending therethrough in which a ball check valve member 98 is disposed

for closing a port 99 in the lower end of the plunger. A pin 100 is provided which extends transversely through the plunger a short distance from the valve member 98 for the purpose of limiting the extent of movement thereof with respect to port 99.

The plunger 95 is journaled at its upper end upon a crank pin 101, Fig. 1, that is carried upon the crank arm 59 and which is eccentric to the axis of rotation of the crank shaft 61 so that as the crank shaft 61 is rotated, the plunger 95 is reciprocated. The passage 97 in the plunger is connected to the passage 87 in the crank arm 59 and crank pin 101, so that fluid lubricant which is forced into the passage 87 in the plunger, flows to the bearings through the passages 87 and 88, the lubricant passing the bearings and the choke passage 102 in the crank arm 59 after which it flows into the crank chamber 17 from whence it may return to the chamber 92 in the piston 91.

The lower end of the plunger, that is, the enlarged head thereof, is provided with a substantially spherical surface 103 which is adapted to engage the inner conical end surface 104 of the piston 91 so as to make sealing engagement therewith on the downstroke of the plunger and maintain such sealing engagement regardless of angular movement of the plunger 95 with respect to the piston 91. The enlarged head 96 is loosely connected to the piston 91 by means of a bushing 108 having a conical end surface 109 flaring downwardly toward the head 96, the bushing being supported on an interiorly extending shoulder 110 in the wall of piston 91, and secured thereon by bending or peening over the end of the piston 91 wall.

When the plunger 95 is raised from the position shown in Fig. 11, it moves a short distance before the enlarged head 96 strikes the conical surface 109 of the bushing 108, and thereby is effected the lost motion or loose connection between the plunger 95 and the piston 91, above referred to.

Upon the upward stroke of the piston plunger 95, the spherical surface of the enlarged head 96 is separated from the conical surface 104 of the piston 91 so that as the piston 91 is moved upwardly by the plunger, oil or lubricant fluid may flow through the opening 93 in the piston past the enlarged head 96 of the plunger and through the port 94 into the compression chamber 89, the ball check valve member 98 at such time remaining seated so that it closes the port 99 in the lower end of the plunger. Upon the downward stroke of the plunger, the spherical surface 103 initially moves into sealing engagement with the conical surface 104 of the piston, thereby preventing any passage of fluid lubricant from the compression chamber 89 into the chamber 92 in the piston and transmitting a downward force to move the piston 91 downwardly. As the piston 91 is moved downwardly by the plunger 95, it exerts a compressive force on the fluid lubricant within the chamber 89 and causes the fluid to pass through the ports 94 and 99, past the check valve ball member 98 into the passage 97, and thence to the bearings through the passage 87. Upon the subsequent upward stroke of the plunger 95, the ball member 98 seats and thereby closes the port 99, thus preventing the fluid in the passage 97 from flowing therefrom back into chamber 89 through the passage 99. As previously stated, during the upward stroke of the plunger 95, the spherical surface of the head 96 separates from the conical surface 104 of the piston, and fluid lubricant flows into the chamber 92 of the pis-

ton due to the gravitational force or pressure head of the fluid lubricant within the crank case, thence through the port 94 in the lower end of the piston into the chamber 89 from whence it is 5 discharged into the passage 97 in the plunger upon the subsequent downward stroke of the plunger.

By reason of the pump construction just described, wherein a free passage is provided for 10 the flow of fluid into the compression chamber under a gravitational head, the compression chamber 89 is completely filled during every cycle of operation of the pump, regardless of the speed of operation of the plunger. Consequently regardless of the speed of operation of the compressor, the bearings for the connecting rods are lubricated properly, thus prolonging the life of the compressor.

In the operation of the compressor, the rotation of the fan 69 within the fan chamber 73 causes air to be drawn into the fan chamber in the manner described and forced through the screened opening 83 in the partition wall 82 into the motor chamber 11 containing the motor armature 65. The large volume of air forced past the motor armature and its associated stator winding maintains the motor at the proper operating temperature. Subsequently the air passes from the motor chamber 11 into the cooling chamber 18 through the openings 105 in the end wall 26 of the casing section 14, around the cylinders 16, and is discharged to the atmosphere through the respective radial passages 31, past the fins 29 and 39 on the cylinders 16 and 35 the head casings 32, thus carrying away the heat generated during the compressing operation of the compressor.

Air for compression is drawn into inlet chamber 24 of the compressor unit through the inlet pipe 30 which is connected thereto, and thence it passes to the inlet chamber 20 surrounding each of the piston cylinders 16 through corresponding passages 25, the air entering the compression chambers 106 above the various pistons 45 56 through a plurality of peripheral ports 107 in the wall of each cylinder 16 when the corresponding piston is at the bottom of its stroke. Upon the upward stroke of each of the pistons, the ports 107 are first closed and then the 50 trapped air is forced past the discharge valve device, previously described, into the associated discharge chamber 33, and is discharged to the receiver pipe 36 through passage 34 and discharge chamber 19.

In the event that it is desired to force air into the compression chambers under pressure, the inlet pipe 30 is closed in any suitable manner and the plugs 28 are removed from their respective threaded openings 27, thereby permitting 60 air under pressure to flow from the motor chamber 11 into the inlet chamber 24 through the threaded openings 27 and from thence through the ports 107 in the cylinders 16 to the compression chamber above the piston. The manner of supplying air to the compression chambers of the compressor is therefore, optional.

It will, therefore, be seen that an improved, compact and self-contained fluid compressor unit has been disclosed wherein is provided an 70 improved sectional casing which serves in directing the flow of cooling air for the compressor and its driving motor in a novel manner, which is adapted to form a crank case chamber, a cooling chamber and a compressed fluid discharge chamber for the compressor in a simple compact

arrangement, and which is adapted to permit fluid under pressure from the cooling chamber of the compressor to be supplied to the compression cylinders of the compressor, while also providing optionally for the supply of fluid at atmospheric or other pressure to the compression cylinders from an external source.

It will also be seen that there has been disclosed an improved compressor of the radial cylinder type in which the fluid inlets for the respective compressor cylinders are controlled by the compressor pistons operating in the cylinders.

It will also be seen, furthermore, that there has been disclosed a compressor wherein is provided an improved plunger pump for circulating 15 fluid lubricant for the moving parts of the compressor, and wherein is provided an improved discharge valve device capable of assembly and disassembly as a unit.

It will be seen, lastly, that there has been disclosed a compressor unit provided with an improved means for cleaning the cooling fluid therefor.

While but one embodiment of my invention is herein disclosed, it is obvious that omissions, 25 additions, and other changes may be made in the construction without departing from the spirit of the invention.

Having now described my invention, what I claim as new and desire to secure by Letters 30 Patent, is:

1. A fluid compressor comprising a casing, a cylinder mounted in said casing, a piston operable in said cylinder, a fluid inlet port in said cylinder, controlled by the movement of said piston, a fluid inlet passage providing an independent connection with the atmosphere for said inlet port, means providing a cooling chamber for said cylinder, means providing a communication between said inlet passage and said cooling chamber whereby fluid supplied to said cooling chamber may also be supplied to said inlet passage, and means for closing the communication between said inlet passage and said cooling chamber.

2. A fluid compressor comprising a casing, a plurality of radially disposed compressor cylinders mounted on said casing, a piston for each of said cylinders operable respectively therein, a fluid inlet passage for each of said cylinders controlled by the movement of the piston in the corresponding cylinder, means providing a passage connecting said inlet passages and having a connection to the atmosphere, means providing a cooling chamber for said cylinders and having a connection between said cooling chamber and said connecting passage whereby fluid supplied to said cooling chamber may also be supplied to said connecting passage, and means for closing said last connection.

3. A fluid compressor comprising a casing, a plurality of radially disposed cylinders mounted in said casing, a fluid compressing piston in each cylinder, a crank shaft operatively connected to said pistons for operating the said pistons in their respective cylinders, and a motor for driving said crank shaft, said casing having an outer arcuate wall, an inner arcuate wall forming a crank case chamber for said crank shaft, and an intermediate arcuate wall forming at one side thereof a cooling chamber for said cylinders and at the opposite side thereof a fluid discharge chamber for said cylinders.
